DESIGN FOR A FAN GUARD

George R. Graff, Toledo, Ohio, assignor to
Wagner Electric Corporation, St. Louis, Mo., a
corporation of Delaware

Application January 6, 1936, Serial No. 60,436

Term of patent 14 years

To all whom it may concern:

Be it known that I, George R. Graff, a citizen
of the United States of America, residing at the
city of Toledo, county of Lucas, State of Ohio,
have invented a new, original, and ornamental
Design for Fan Guards, of which the following
is a specification, reference being had to the ac-
companying drawing, forming a part thereof.

In the drawing Figure 1 is a front elevation of
a fan guard made in accordance with my new
design; Figure 2 is a side view; and Figure 3 is a
section taken on the line 3—3 of Figure 2.

I claim:

The ornamental design for a fan guard as
shown.

GEORGE R. GRAFF.
